JOHN M. COOTE AND CLARENCE E. PRYOR, OF ELIZABETH, NEW JERSEY.

RADIO REPRODUCING ATTACHMENT FOR PIANOS.

Application filed June 18, 1927. Serial No. 199,822.

This invention relates to radio reproducing attachment for piano sounding boards and the like.

Pursuant to our invention, the electrical 5 radio reproducing device actuated by the radio receiving set is adjustably positioned relatively to the sounding board of a piano, usually at the region of engagement of the bridge of the piano with the sounding board, 10 and preferably at the location of passage of the middle C or C4 wires over the bridge.

Pursuant to the preferred forms of our invention, the actuated element of the radio reproducing device is attached by adjustable 15 pressure means to a location interiorly within the material of the sounding board and of the bridge, whereby the vibrations imparted by the actuated member to the sounding board are reproduced effectively by the sounding 20 board vibrating as a whole.

It is usually convenient in upright and grand types of pianos to attach our attachment to the rear of the sounding board.

Further features and objects of the invention will be more fully understood from the following detail description and the accompanying drawings, in which

Fig. 1 is an elevation of the rear of an upright form of piano, showing our radio reproducer attached thereto;

Fig. 2 is a sectional elevation on line 2—2 of Fig. 1, on a greatly enlarged scale;

Fig. 3 is a sectional elevation on line 3—3 of Fig. 1;

Fig. 4 is a sectional elevation on line 4—4 of Fig. 3, on an enlarged scale;

Fig. 5 is a detail sectional elevation of certain parts;

Fig. 6 is a detail view of a modification; and

Fig. 7 is a detail view showing the assembly of our invention in a grand piano.

Referring to the drawings, the piano 10 may be of any form, and includes a suitable sounding board 11, associated with the usual treble bridge 12 disposed on the inner face of the sounding board, for locating the wires corresponding to the keys of the piano; the key actuating and damping parts are of the usual or any approved type.

50 In the instance of an upright piano, as il-

lustrated, the sounding board 11 is located in substantially a vertical plane, and the rear structure of the piano includes a number of vertical stanchions of suitable material extending from the bottom rail 14 to the top 55 rail 15.

It is convenient to attach our radio reproducer 16 between two central stanchions 13^a, 13^b, to locate the actuated element 17, see Figs. 2 and 3, of our radio reproducing device 16 60 in substantially horizontal alignment with the intersection of the bridge 12 with the sounding board 11 between such central stanchions 13^a, 13^b.

Usually, the sounding board of a piano is 65 held to the bridge by a button 18 which is secured by a screw or a dowel pin. Such button is preferably of harder wood or other material than the sounding board.

An effective manner of assembly of our invention is had by removing the screw, then 70 removing the button, then boring a hole 19 at the location through the sounding board and into the bridge, and then inserting a dowel pin 20 of maple or like material, which pin 75 20 tightly fits the bored hole. The pin 20 is glued fast in the bored hole.

The aperture 21 is bored through substantially the center of the pin 20, but not extending entirely through the pin, thus leaving the solid bottomed portion 20^a. The button 18 is replaced and secured by glue.

Any suitable form of electrically actuated radio reproducing device may be employed, which comprises usually one or more "voice" 85 coils 22, the windings of which are connected with the terminals of the plug or of the last audio stage of the radio receiving set, and also usually comprising an armature 23 which is vibrated in correspondence to variations of the electrical current passing through the windings of the "voice" coils. Such radio reproducing device usually includes also a permanent magnet and a core controlling the range of movement of the 90 armature and the path of the electro-magnetic flux created jointly by the permanent magnet and the variations of the current passing through the "voice" coils 22.

We have shown the vibrated member 24 100

mechanically connected at a suitable location to the armature 23 and extending substantially horizontally when my attachment 16 is secured in position on the vertical stanchions 13^a, 13^b of an upright piano. Preferably the vibrating member 24 is of solid metal stock, such as a round metal wire of a diameter of at least one-sixteenth of an inch, which is reclined at its free end within the bored opening 26^a of the metal rod 26 of approximately three-thirty seconds of an inch outer diameter. The free end of the member 24 is soldered as indicated at 24^a within the bored opening 26^a. The inner end 26^b of the rod 26 is threaded to be screwed into the bore of the plug 27. The bore of the plug 27 does not extend through the bottom of the plug 27. The leather plug serves to preclude contact at any location between the rod 26 and the pin 20. Generally speaking, the highest grades of leather give best results and we have obtained optimum results by the use of oak tanned leather of the back of the hide.

As is indicated in Figs. 2 and 3, our radio reproducing attachment is conveniently secured in position by means of a supporting and adjusting bar 28 extending between the stanchions 13^a and 13^b and adjustably secured thereto by means of the screws 29, 30 passing through suitable openings in the bar 28.

Our radio reproducing attachment is assembled and adjusted by means of the screws 29, 30 and the member 24 and rod 26 integrally connected to one another at the set position, as above described, to locate the end 26^b in firm engagement under pressure with the leather shielding 27. Such adjustment is made while the movable or actutable parts of the radio reproducing device are quiescent and also to locate the armature to have free vibration under electro-magnetic actuation. Such relationship of the parts enables the screws 29, 30 to be further adjusted in their tapped openings in the braces 13^a, 13^b if desired, or from time to time, loosened or tightened, to thereby correspondingly adjust the bar 28 and therewith our radio reproducing unit 16, including its actuated members 24, 26, relative to the sounding board 11 and the bridge 12, for attaining optimum reproduction and also for permitting a range of variation of the emitted volume of the reproduced sounds.

Preferably, our radio reproducing unit 16 comprises a laminated core 31 which is secured to and extends from one leg 32 to the opposite leg 33 of a permanent magnet 34. The armature 23 is preferably anchored at its fixed end 23^a to a rigid support, such as the bar 35, in turn rigidly secured at its ends to the legs 32, 33 of the permanent magnet 34, and the actuated member 24 is secured to the

armature 23 at a location between its fixed end 23^a and its free end. Such rigid support bar 35 may advantageously be subject to adjustment by employing the screw-threaded member having a thumb-head 36 for exerting a twist on the bar 36 within ranges of high pressure per square inch, thus attaining an adjustment imposing high compression on the bar 35 and maintaining the bar 35 rigid for every adjusted position.

Preferably, when our invention is applied to the rear or other inaccessible part of the piano or like instrument, we provide a rod or arm 37 extending at its free end 38 to the side or other readily accessible portion of the piano and attached at its opposite end to the thumb-head 36 or equivalent, to enable the adjusting member 36 to be regulated by pushing and pulling from time to time to any desired set position. The free end 38 of the rod 37 may be loosely passed through a screw-eye 40 or equivalent.

The clamping and regulating bar 28 may advantageously be standardized and provided with a plurality of pairs of openings 41 and 42, 41^a and 42^a, 41^b and 42^b, etc., for varying positions of the set bolts 43, 44, or equivalent of the radio reproducing unit, to accommodate ready variable positions of the unit relative to the treble bridge or other location with respect to the sounding board, and for different makes and types of pianos.

In Fig. 6, we have shown a modification of screw-threading the free end of the wire 24 and providing reverse-threading at the abutting end of the wire 26, and employing a turn-buckle 50 to adjust the final position. The wire 24 is soldered to the turn-buckle 50 at final setting as indicated at 51 and similarly at 52 to solder the wire 26 to the turn-buckle 50.

In Fig. 7, we show our invention applied to a grand type of piano in which the sounding board 11 is in horizontal position. In this instance, the plug 21 is inserted from the bottom similarly as in an upright type of piano, and an opening 53 is drilled through the bridge of smaller diameter than the opening 19. The wire or rod 26 is passed through the opening 53 and brought into damped securement within the leather plug 27, similarly as hereinabove set forth.

The thickness of the leather shielding 27 intervening between the actuated member 26 and the maple pin or equivalent should be of the magnitude of one-sixteenth of an inch or less to thereby provide for a sufficiently firm operating connection between the reciprocally actuated member 26 and the pin, which operating connection in both directions of reciprocatory action is enhanced by the leather shielding 27.

Whereas, we have described our invention by reference to specific forms thereof, it will

be understood that many changes and modifications may be made without departing from the spirit of the invention.

We claim:

5. 1. The combination with a sounding board of a piano or the like, including elements for supporting the sounding board and further including a bridge for said sounding board, said bridge being provided with a bottomed recess, of an electro-magnetic device comprising coil means, an armature responsive to the variations of the current passing through the winding of said coil means, an element actuated by said armature, means for supporting said electro-magnetic device on said supporting elements, the free end of said actuated element being disposed under pressure within said bottomed recess, and means for adjusting the degree of pressure between said actuated element and said bridge. 70
10. 2. The combination with a sounding board of a piano or the like, including elements for supporting the sounding board and further including a bridge for said sounding board, said bridge being provided with a bottomed recess, of an electro-magnetic device comprising coil means, an armature responsive to the variations of the current passing through the winding of said coil means, a core for said coil means, means for adjusting the normal clearance between said armature and said core, an element actuated by said armature, means for supporting said electro-magnetic device on said supporting elements, the free end of said actuated element being disposed under pressure within said bottomed recess, and means for adjusting the degree of pressure between said actuated element and said bridge. 80
15. 3. The combination with a sounding board of a piano or the like, including elements for supporting the sounding board and further including a bridge for said sounding board, said bridge being provided with a bottomed recess, of an electro-magnetic device comprising coil means, an armature responsive to the variations of the current passing through the winding of said coil means, a core for said coil means, compressional means for adjusting the normal clearance between said armature and said core, an element actuated by said armature, means for supporting said electro-magnetic device on said supporting elements, the free end of said actuated element being disposed under pressure within said bottomed recess, and means for adjusting the degree of pressure between said actuated element and said bridge. 85
20. 4. The combination with a sounding board of a piano or the like, including elements for supporting the sounding board, of an electro-magnetic device comprising coil means, an armature responsive to the variations of the current passing through the winding of said coil means, an element actuated by said armature, means for supporting said electro-magnetic device on said supporting elements, said sounding board being provided with a bottomed recess, a plug of resilient dense material disposed at the bottom of said bottomed recess, the free end of said actuated element being in contact under pressure with said disk, and means for adjusting the degree of pressure between said actuated element and said sounding board. 90
25. 5. The combination with a sounding board of a piano or the like, including elements for supporting the sounding board, of an electro-magnetic device comprising coil means, an armature responsive to the variations of the current passing through the winding of said coil means, an element actuated by said armature, means for supporting said electro-magnetic device on said supporting elements, said sounding board being provided with a bottomed recess, a plug of leather disposed at the bottom of said bottomed recess, the free end of said actuated element being in contact under pressure with said disk, and means for adjusting the degree of pressure between said actuated element and said sounding board. 95
30. 6. The combination with a sounding board of a piano or the like, including elements for supporting the sounding board, and further including a bridge for said sounding board, said bridge being provided with a bottomed recess, of an electro-magnetic device comprising coil means, an element actuated by said coil means, means for supporting said electro-magnetic device on said supporting elements, a plug of resilient dense material disposed at the bottom of said bottomed recess, the free end of said actuated element being disposed under pressure against said plug, and means for adjusting the degree of pressure between said actuated element and said plug. 100
35. 7. The combination with a sounding board of a piano and the like, including a bridge and associated elements for supporting the sounding board, said bridge being provided with a bottomed recess substantially at the location of the passage over the bridge of the wires corresponding to the middle C tone, of an electro-magnetic device comprising coil means, an armature responsive to the variations of the current passing through the winding of said coil means, an element actuated by said armature, means for supporting said electro-magnetic device, the free end of said actuated element being disposed under pressure within said bottomed recess, and means for adjusting the degree of pressure between said actuated element and said bridge. 110
40. 8. The combination with a sounding board of a piano and the like including a bridge and associated elements for supporting the sounding board, of an electro-magnetic device com- 115
45. 120
50. 125
55. 130

prising coil means, an armature responsive to the variations of the current passing through the winding of said coil means, an element actuated by said armature, means for supporting said electro-magnetic device to locate said actuated element in contact with said sounding board corresponding to the location of the passing over said bridge of the wires of the middle C tone, the free end

of said actuated element being disposed under pressure against said sounding board and said bridge, and means for adjusting the degree of pressure between said actuated element and said bridge.

In testimony whereof we have signed this 15 specification this 16th day of June, 1927.

JOHN M. COOTE.

CLARENCE E. PRYOR.
